(57) **CLAIM**

The ornamental design for an extinguisher for aerosol generators, as shown and described.

DESCRIPTION

FIG. 1 is a front, top, and right side perspective view of a first embodiment of an extinguisher for aerosol generators showing the new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a front, top, and right side perspective view of a second embodiment thereof.

FIG. 9 is a front, top, and right side perspective view thereof in a use position;

FIG. 10 is another front, top, and right side perspective view thereof in a use position;

FIG. 11 is a front elevational view thereof.

FIG. 12 is a rear elevational view thereof.

FIG. 13 is a left side elevational view thereof.

FIG. 14 is a right side elevational view thereof.

FIG. 15 is a top plan view thereof.

FIG. 16 is a bottom plan view thereof.

FIG. 17 is a front, top, and right side perspective view of a third embodiment thereof.

FIG. 18 is another front, top, and right side perspective view thereof;

FIG. 19 is a front, top, and right side perspective view thereof in a use position;

FIG. 20 is a front elevational view thereof.

FIG. 21 is a rear elevational view thereof.

FIG. 22 is a left side elevational view thereof.

FIG. 23 is a right side elevational view thereof.

FIG. 24 is a top plan view thereof; and,

FIG. 25 is a bottom plan view thereof.

The broken lines in the drawings depict portions of the extinguisher for aerosol generators that form no part of the claimed design.
